Primary Examiner — Kevin K Rudzinski(74) *Attorney, Agent, or Firm* — Perkins IP Law Group LLC; Jefferson Perkins(57) **CLAIM**

We claim the ornamental design for a winged nut, as shown and described.

DESCRIPTION

FIG. 1 is a top perspective view of the claimed design for a winged nut;

FIG. 2 is a bottom perspective view of the wing nut shown in FIG. 1;

FIG. 3 is a side view of the wing nut shown in FIG. 1, an opposite side view thereof being identical to the side shown; FIG. 4 is a bottom view of the wing nut shown in FIG. 1; and,

FIG. 5 is a top view of the wing nut shown in FIG. 1. The dashed lines on the claimed design in FIGS. 1-5 depict environmental structure that form no part of the claimed design.
